PROCESS FOR FORMING DESIGNS.

Application filed March 30, 1927. Serial No. 179,416.

The present invention relates to processes for forming designs of desired shape or configuration on substances capable of being rendered plastic by heat; and its object is to provide such a process whereby permanent designs may be formed readily and economically on such substances.

This object is attained by the process particularly described in the body of this specification, and preferably by means of the apparatus hereinafter described and illustrated by the accompanying drawings, in which:—

Figure 1 is a plan view of a sheet of material displaying certain designs formed thereon; i. e., letters of the alphabet;

Figure 2 is a sectional view (enlarged) of the left-hand end portion thereof taken on line 2—2 of Figure 1;

Figure 3 is a plan view of a plate having design-outlining openings therethrough, and being a part of the apparatus whereby the process may be carried out; and

Figure 4 is a side view of another part of said apparatus and a sectional view of said sheet of material and of the left-hand end portion of said plate, taken on line 4—4 of Figure 3.

In these drawings is shown a sheet designated generally 1 comprising a base 2 composed of a substance which may be rendered plastic or soft by being subjected to heat—i. e., bituminous material or the like—and an outer coating 3 of granulated material (such as slate or rock particles) adhering to the base by reason of being partially embedded therein while the same was heated to a sufficiently soft or plastic condition, such sheet thus composed being a so-called "asphalt" shingle or roofing strip of a well-known type.

To form designs on this sheet, areas thereof whose outlines define the desired design are heated sufficiently to soften or render plastic corresponding areas of the base 2, the remainder of the base outside such areas not being thus heated. The substance of the base within these heated areas rises (under the heating action) between the particles 3, so that while thus hot and plastic granulated particles 4 of slate, rock or the like are applied to such plastic areas and partially embedded therein; whereupon, such particles 4 being of a color different from that of the particles 3, thus display in contrast there-

with the desired design, as (for instance) the letters of the alphabet and punctuating periods shown in the drawings.

In carrying out this process, apparatus may be employed comprising a plate 5 of sufficiently heat-nonconducting material, as (for instance) asbestos, and having openings 10 therethrough outlining the desired design is laid on the coated surface of the sheet 1, and heat is applied to the outer surface of said plate, as by impressing thereon the hot member 6 having a flat under surface 7 contacting said sheet. This member is held in such contact long enough to soften the portions of the base 2 which underlie and register in position with said openings, and thereupon (the member 6 being removed) the particles 4 are applied to the heated areas and partially embedded therein while plastic.

A base 2 not coated with particles 3 may be thus heated in desired areas, whereupon particles 4 may be applied thereto to display the design; or, a base 2 coated with particles 3 may be heated in design-defining areas so that the substance of the base may rise between said particles and thus display the design without applying particles 4 to such heated and plastic areas.

I claim:

1. The process of forming designs on a substance capable of being made plastic by heat, which consists in heating sufficiently to render plastic such area only of said substance as defines the design and then applying to and embedding in said plastic area granulated material contrasting in appearance with the remaining area of said substance.

2. The process of forming designs on a substance comprising a base capable of being made plastic by heat and a coating of particles embedded therein, which consists in heating sufficiently to render plastic such area only of the base as defines the design and to cause said plastic substance of the base to pass outwardly between said particles.

3. The process of forming designs on a substance comprising a base capable of being made plastic by heat and a coating of particles embedded therein, which consists in heating sufficiently to render plastic such area only of the base as defines the design

- and to cause said plastic substance of the base to pass outwardly between said particles, and then applying to and embedding in said plastic area of the substance of the base granulated material contrasting in appearance with the first-mentioned particles. 5
4. The process of forming designs on a sheet comprising a substance capable of being made plastic by heat, which consists in applying to said substance a plate having heat-conducting openings therethrough defining the design, and supplying sufficient heat to the substance through the openings to render plastic the area of the substance 10
- 15 registering with the openings.
5. The process of forming designs on a sheet comprising a substance capable of being made plastic by heat, which consists in applying to said substance a plate having heat-conducting openings therethrough defining the design, and supplying sufficient heat to the substance through the openings to render plastic the area of the substance 20 registering with the openings, and then applying to and embedding in such plastic area granulated material contrasting in appearance with the remaining area of the sheet. 25
6. The process of forming designs on a roofing sheet containing bituminous material capable of being made plastic by heat, which consists in heating sufficiently to render plas- 30
- tic such area only of said sheet as defines the design and then applying to and embedding in said plastic area granulated material contrasting in appearance with the remaining area of said sheet. 35
7. The process of forming designs on a roofing sheet comprising a base containing bituminous material capable of being made plastic by heat and a coating of particles embedded therein, which consists in heating sufficiently to render plastic such area only of the base as defines the design and to cause said plastic substance of the base to pass outwardly between said particles. 40
8. The process of forming designs on a roofing sheet comprising a base containing bituminous material capable of being made plastic by heat and a coating of particles embedded therein, which consists in heating sufficiently to render plastic such area only of the base as defines the design and to cause said plastic substance of the base to pass outwardly between said particles, and then applying to and embedding in said plastic area of the substance of the base granulated material contrasting in appearance with the first-mentioned particles. 50
- 55

In testimony whereof I have hereunto set my hand at Grand Rapids, Michigan, this 60
9th day of March, 1927.

ORLO W. JUDKINS.
